DIRECTION SIGNAL

John F. Campbell, Modesto, Calif.

Application November 9, 1929, Serial No. 405,971

1 Claim. (Cl. 177—327)

This invention relates to direction giving signal devices for motor vehicles, my principal object being to provide a device of neat appearance and having no moving parts and in which the signals 5 are given by means of artificial lights, which are so arranged that right, left or stop signals may be readily displayed in a very clear and distinct manner. The signal device itself is also so arranged that these signals, from the same sources 10 of light, will be visible with equal clarity both from the front and the rear of the vehicle. Though the signal is intended for day or night use it is especially effective at night when arm signals if given are not easily seen.

15 A further object of the invention is to produce a simple and inexpensive device and yet one which will be exceedingly effective for the purpose for which it is designed.

These objects I accomplish by means of such 20 structure and relative arrangement of parts as will fully appear by a perusal of the following specification and claim.

In the drawing similar characters of reference indicate corresponding parts in the several views: 25 Fig. 1 is a front elevation of my improved signal device.

Fig. 2 is a sectional plan of the same on the line 2—2 of Fig. 1.

Fig. 3 is a diagram of the circuit means employed with the signal.

Referring now more particularly to the characters of reference on the drawing, the device comprises a casing 1 of suitable character and of substantially rectangular form and relatively 35 shallow; having a suitable base bracket 2 whereby it may be mounted in a rigid manner on a wheel fender of the vehicle or other suitable location. Transparent panes 3 are mounted in the casing across the front and rear faces of the 40 same. Just inwardly of the panes opaque and preferably black colored plates 4 are disposed in which diagonally extending arrow shaped openings 5 are cut, which cross each other intermediate their ends as shown. The openings in the 45 two plates are symmetrical with each other and their edges are connected throughout their extent by opaque walls 6. A pair of chambers 7 extending from the front to the back of the casing and intersecting or merging into each other between 50 their ends are thus formed.

Disposed in these chambers in symmetrically spaced relation to the side walls thereof are transparent glass tubes 8, crossing each other intermediate their ends and extending the full length 55 of the chambers. These tubes are bent at their

upper ends in the simulation of arrow heads as shown at 9 conforming to the shape of the chambers at said ends. These tubes are filled with neon gas treated in such a way that when an electric current is passed through the same the 60 gas glows brightly with a certain color and the entire tube becomes illuminated and its outline sharply set forth.

The tubes extend in parallel clearance relation to the sides of the chambers throughout their 65 length except at the ends, where they are bent to project through and be supported by the side walls of the chambers near their ends. The tubes at one end are provided with electrodes 10 which are grounded onto the casing 1, their other ends 70 also having electrodes connected to wires 11 leading to a switch 12 which is connected to the battery 13 of the car; individual vibrator coils indicated at 14 being interposed in the circuits between the switch and the tubes to step up the 75 voltage of the current to the extent necessary to cause the gas to be properly influenced or charged. The switch is located at a point in the vehicle 80 convenient to the driver and is of the three point selective type, or so that either tube at a time or both tubes together may be included in the circuit when the switch is closed. When the tube pointing to the right of the car is illuminated a right turn is indicated; the illumination of the tube pointing to the left denotes a left turn; and 85 when both tubes are illuminated together a cross is formed which denotes stop.

By reason of the above construction and arrangement it will be seen that direction giving arrows are provided whose outlines, being continuous, are sharp and unmistakable. Also this 90 particular shape and construction of the chambers allows all the light to be utilized in signal giving, since none of the light is lost in blind pockets or dead spaces in the casing, as is the 95 case when the desired shape or outline of the signal is obtained by merely cutting a slot in an opaque end panel. Further the chambers being open from the back to the front of the casing without any obstructions it will be obvious that 100 the signal formed by the illumination of the tubes is as plainly visible from in front of the casing as from the rear of the same.

From the foregoing description it will be readily 105 seen that I have produced such a device as substantially fulfills the objects of the invention as set forth herein.

While this specification sets forth in detail the present and preferred construction of the device, still in practice such deviations from such detail 110

may be resorted to as do not form a departure from the spirit of the invention, as defined by the appended claim.

Having thus described my invention what I claim as new and useful and desire to secure by Letters Patent is:

A direction signal comprising a relatively shallow hollow casing, opaque front and back walls on the casing, a pair of uninterrupted narrow

10

slot like arrow-shaped chambers formed within in the casing and intersecting each other, the opaque front and back walls being provided with corresponding intersecting transparent areas in each wall adjacent the chambers, and a neon tube disposed within and extending substantially the full length of each chamber and following the arrow-shaped contour thereof.

JOHN F. CAMPBELL.
